UNITED STATES PATENT OFFICE.

ERNEST C. BRAGG, OF BALTIMORE, MARYLAND.

HOSE-REEL.

1,291,387.

Specification of Letters Patent.

Patented Jan. 14, 1919.

Application filed October 16, 1918. Serial No. 258,371.

To all whom it may concern:

Be it known that I, ERNEST C. BRAGG, a citizen of the United States, residing at Baltimore, in the State of Maryland, have invented certain new and useful Improvements in Hose-Reels, of which the following is a specification, reference being had to the accompanying drawings.

This invention relates to certain improvements in hose reels, and it is an object of the invention to provide a device of this general character with novel and improved means whereby the hose may be readily and quickly disengaged from the reel.

It is also an object of the invention to provide a device of this general character embodying novel and improved means whereby the nozzle end of a hose may be effectually held by the reel, and wherein said nozzle end of the hose may be quickly released when it is desired to use the hose.

An additional object of the invention is to provide a wheel supported for rotary movement and wherein an end portion is provided with arms normally radiating from a member disposed axially of the reel for holding the hose upon the reel, together with means for imparting axial movement to the member in a direction to throw the arms into a position to permit the hose wound upon the reel to drop therefrom.

The invention consists in the details of construction and in the combination and arrangement of the several parts of my improved hose reel whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a vertical sectional view with portions in elevation of the reel constructed in accordance with an embodiment of my invention, one of the hose supporting arms being omitted;

Fig. 2 is a transverse sectional view taken through the lower end portion of the winding drum as herein included;

Fig. 3 is a fragmentary view partly in top plan and partly in section illustrating the connection between the hose retaining

arms and the operating rod coacting therewith;

Fig. 4 is a fragmentary view partly in section and partly in elevation of the lower portion of my improved reel with the hose retaining arms in releasing position;

Fig. 5 is a fragmentary view in elevation of the hook member as herein employed for holding the operating lever in one position;

Fig. 6 is a fragmentary view partly in section and partly in elevation of the mechanism coacting with the nozzle end portion of a hose.

As disclosed in the accompanying drawings, S denotes a support which may be either stationary or movable, and which is provided with an opening 1 defined by an upstanding elongated sleeve 2. The lower or inner end of the sleeve 2 is provided with an outstanding flange or collar 3 whereby the sleeve is held to the support S by the bolts 4 or the like. Underlying the support S and held in contact therewith by the bolts 4 is a plate 5 having a central opening registering with the opening 1 and of substantially the same diameter.

The marginal portion of the plate 5 is provided with an annular seat 5^a, upon which rests the inner marginal portion of an annular head H.

The head H is suitably secured within the upper portion of a drum D, and which drum gradually tapers toward its lower end. The lower end of the drum D is closed by a head H' which is provided with a series of equidistantly spaced and radially disposed slots 6, preferably four in number. The lower portion of the side wall of the drum D is provided with the openings 7 in communication with the outer ends of the slots 6.

Disposed through the sleeve 2 and within the drum D is an elongated member or rod M which is of a length in excess of the longitudinal diameter of the drum D, so that when the lower end of the member or rod M rests upon the lower head H' of the drum, the upper portion of said member or rod will also be disposed through the sleeve 2 as is clearly illustrated in Fig. 1 of the accompanying drawings.

The lower end portion of the member or rod M has radiating therefrom the arms 8 in alignment with the openings 7 when the member or rod M is at the limit of its downward movement. Pivotedly engaged with

each of the arms 8 is the inner end portion of an elongated hose retaining arm 9 which extends exteriorly of the drum D through the openings 7 when the member or rod M is 5 at its limit of downward movement. The arms 9 serve to hold the portions of the hose wound around the drum D normally against displacement, but upon upward movement being imparted to the member or rod M, the 10 arms 9 will drop inwardly as indicated in Fig. 4 so that the hose wound around the drum D will readily drop therefrom and which action is facilitated by the tapered formation of the drum.

15 The major portion of the member or rod M from its upper end is provided with a series of annular teeth 10 having in mesh therewith the teeth 11 of a member 12 rotatably supported by the bracket 2, and which 20 teeth extend through a slot or opening 14 produced in the sleeve 2. Radiating from the member 12 is an operating handle 15. When said handle 15 is in substantially a vertical position, the member or rod M is at 25 the limit of its downward movement or in contact with the lower head H'. When it is desired to elevate the member or rod M in order to retract the arms 9 to permit the hose wrapped around the drum D to drop 30 therefrom, it is only necessary to pull downwardly on the lever 15 until the same assumes substantially a horizontal position. In order to hold the lever 15 in such position, I provide a support S with the up- 35 standing resilient hook member 16 which engages over the lever 15.

In winding a hose about the drum D, the union end of the hose is adapted to be engaged within a spring clamp 16 or its 40 equivalent carried by an outer end portion of an arm 9, and upon rotation of the drum D the hose is coiled or wound therebetween. The nozzle end portion of the hose is positioned between the members 17 and 18 extending outwardly from the drum D. The member 17 is stationary relative to the drum D, and has an end portion extending inwardly of the drum through an opening 19 and said inner end portion is suitably affixed 50 to the brackets 20 depending from the upper head H. The member 18 has its inner end portion detachably connected as at 21 with a sliding arm 22 supported by the upwardly facing hook member 23 arranged at the 55 lower end of each of the brackets 20, while the member 18 in advance of its connection 21 has sliding engagement with a bracket 24 depending from the exterior portion of the member 17. The inner end portion of 60 the sliding arm 22 has pivotally engaged therewith a rigid link 25 which is also pivotally engaged with a gear wheel 26 rotatably mounted within the drum D, and which is in mesh with the annular teeth 10 65 of the member or rod M.

As is clearly indicated in Fig. 1, it will be noted that upon upward movement of the rod M the gear 26 will be caused to rotate in a direction to draw the arm 22 and the member 18 inwardly a distance to release the nozzle end portion of the hose, so that when the hose is dropped from the drum D the nozzle end portion will generally be on top so that the hose may be quickly put into operation, and which is of especial importance when my improved reel is employed in connection with fire hose. 75

When the member or rod M is returned to its lowermost position, the sliding arm 22 and the member 18 will be forced outwardly 80 and in order to properly engage the nozzle end portion of a hose between the members 17 and 18, the member 18 must be first disengaged from the arm 22 and then connected therewith. 85

In order to maintain the handle 15 in its vertical position, I find it of advantage to have freely engaged with the upper end portion of the member or rod M a spring clasp 27 which serves to hold the arm 15 against 90 downward movement until pull is imposed directly thereon.

From the foregoing description, it is thought to be obvious that a hose reel constructed in accordance with my invention is 95 particularly well adapted for use by reason of the convenience and facility with which it may be assembled and operated, and it will also be obvious that my invention is susceptible of some change and modification 100 without departing from the principles and spirit thereof, and for this reason I do not wish to be understood as limiting myself to the precise arrangement and formation of the several parts herein shown in carrying out my invention in practice except as hereinafter claimed. 105

I claim:

1. A reel of the class described comprising a drum tapered toward one end, retaining arms normally radiating from the smaller end of the drum, means for adjusting said arms into an operative position, means carried by the drum for detachably engaging an end portion of a hose wound about the drum, and means operated by the means for throwing the arms into an inoperative position for releasing said end portion of the hose. 110

2. A reel of the class described comprising a rotatably supported drum, a member mounted for endwise movement at the axial center of the drum, arms normally rotating from the drum and pivotally engaged with said member, means for imparting endwise movement to the member whereby said arms may be moved into or out of operative position, and a clamping means carried by the drum and comprising a stationary member, a movable member, and means operatively 120

115

125

130

engaged with said movable member of the clamp and endwise movable member for moving the movable member of the clamp into released position upon movement of the 5 endwise movable member in a direction to render the arms inoperative.

3. A reel of the class described comprising a hollow drum supported for rotation, an end of the drum being closed and provided 10 with radially disposed slots, an endwise movable member extending within the drum at the axial center thereof and normally contacting with said closed end, retaining arms pivotally engaged with the inner end portion 15 of the endwise movable member and extending through the slots, and means for imparting movement to said endwise movable member.

4. A reel of the class described comprising 20 a hollow drum supported for rotation, an end of the drum being closed and provided with radially disposed slots, an endwise movable member extending within the drum at the axial center thereof and normally 25 contacting with said closed end, retaining arms pivotally engaged with the inner end portion of the endwise movable member and extending through the slots, and a movable member supported exteriorly of the 30 drum and engageable with the endwise movable member for imparting movement thereto.

5. A reel of the class described comprising 35 a hollow drum, an endwise movable member extending therein, a rotary member supported within the reel and rotated upon move-

ment of the endwise movable member, a stationary contact arm carried by the drum and extending exteriorly thereof, a movable clamping member extending exteriorly of 40 the drum, and an operative connection between the movable member of the clamp and the rotary member whereby said movable member is moved into inoperative position upon movement of the endwise movable 45 member in one direction.

6. A reel of the class described comprising a drum, retaining arms carried thereby, a hose clamping means carried by the drum, and means for rendering the retaining arms 50 and the clamping means inoperative.

7. A reel of the class described comprising a drum, retaining arms carried thereby, a hose clamping means carried by the drum, and means for rendering the retaining arms 55 and the clamping means inoperative, said drums being tapered.

8. A device of the character described comprising a drum, retaining means carried thereby and movable into and out of operative position, clamping means carried by the drum, and means for rendering the clamping means inoperative when the retaining means are moved into inoperative position. 60

In testimony whereof I hereunto affix my signature in the presence of two witnesses.
